FRED GRAHAM, OF LUFKIN, TEXAS, ASSIGNOR TO LUFKIN FOUNDRY & MACHINE COMPANY, OF LUFKIN, TEXAS

COUNTERBALANCE FOR PUMPING RIGS

Application filed February 3, 1928. Serial No. 251,505.

My invention relates to means for use on a pumping rig to counterbalance the weight of the pump rods and the load carried thereby. In pumping deep wells for oil, water and the like, the standard rig is often employed. In such a rig the pump rods, piston and its load of fluid is raised and lowered by means of a walking beam to one end of which the rods are attached. The walking beam is 10 rocked by means of a pitman connected with a rotating crank arm. Where the load is heavy, as in deep wells, the upward stroke of the pump is the power stroke, the load dropping by gravity on the down stroke. 15 The jerk or strain exerted by the load upon the rods on the down stroke is sometimes severe and means must be taken to counterbalance this drop and to assist in raising the load thereafter.

- 20 It is an object of my invention to provide a counterbalance weight which may be attached to the pitman of the operating rig and be capable of connection with the crank arm when the pump is operating. 25 It is desired that the weight be capable of ready attachment or detachment from the crank arm when desired.

Referring to the drawings herewith, wherein a preferred embodiment of my invention is 30 illustrated, Fig. 1 is a front elevation of the type of weight used as a counterbalance, the pitman being broken away.

Fig. 2 is a side elevation of the counterweight; and

35 Fig. 3 is a front elevation of my device shown in position upon a pitman as used upon the ordinary pumping rig.

The view shown in Fig. 1 illustrates the equipment with which the counterbalance is 40 particularly designed to operate, it being understood, however, that it may be employed on other similar devices. The walking beam 1 is shown as supported upon the usual Samson post 2, the walking beam being operated 45 through a pitman 3 connected to a wrist pin 4 secured within one of the openings 5 in a crank arm 6. Said crank arm is secured upon a shaft 7 mounted in jack posts 8 upon a supporting platform 9. Said jack posts 50 are reinforced by brace rods 10 in the usual

manner and adapted to depend below the end of said pitman. The shaft 7 is adapted to be rotated through a band wheel 11 secured on said shaft and acting as a pulley for the usual belt drive employed with this type of pumping outfit. It is to be understood that the forward broken end of the walking beam is secured to the pump rod in the usual manner, this being the ordinary standard pumping rig well known in the art and forming in itself 60 no part of my invention.

In order to counterbalance the heavy load of the pump rods and the piston and fluid above the same I contemplate placing adjacent the lower end of the pitman 3 a counterbalance weight indicated generally at A. This counterbalance weight is made up of an upper yoke member 12 which has two arms spaced apart a sufficient distance to fit about the pitman. As shown in Fig. 1, the pitman 70 3 has a lower U-shaped bearing support 15 to house the two bearing blocks 16 through which the wrist pin opening is formed. The upper yoke member 12 is widened out toward the lower end and formed with longitudinal 75 openings therethrough to receive bolts 17. There is also a lower plate 18 at the opposite end of the bolts 17 provided with openings to receive said bolts. Between the plates 18 and 12 I may place a plurality of plates 19 80 forming weights and, as will be obvious, the number of weights secured on the bolts 17 in the manner shown may be varied to accommodate the particular pumping equipment upon which it is used. In deep wells 85 where the load is heavy a large number of such weights may be employed.

The upper yoke 12 of the counterbalance weight is secured to the pitman by means of a through bolt 20, extending through the 90 arms of the yoke 12 and transversely through the pitman. This bolt secures the weight firmly to the pitman in such a manner as to interfere in no way with the engagement of the pitman with the wrist pin upon the crank 95 arm.

In operating a pumping equipment provided with my counterbalance, the weights will be placed upon the lower ends of the 100 pitman in such a way as to be supported upon

the wrist pin and the crank arm and in such manner that on the upstroke of the pump rods the weight will assist in the raising of the rod and in the downstroke of the pump rods the crank will be moving upwardly and the counterbalance weight will resist the sudden dropping of the load of the pump rods. In this manner an even and balanced action upon the power will be obtained and a smooth 10 operation of the pump will result.

It is necessary to remove the pump rods and plunger from the well at intervals for repair and in so doing the pitman is disengaged from the crank arm and the band 15 wheel is used to transmit power to the hoisting device for raising the rods. When this is done, the weight is removed from the crank arm by releasing the same from the wrist pin and the weight is allowed to rest upon the 20 platform out of the way while the band wheel is rotating in performing the hoisting operation. It will act to hold the pitman and walking beam in stationary position so that no interference of the same with the hoisting 25 operations will be experienced. When it is thereafter desired to resume pumping operation, the counterbalance may be raised and the pitman secured upon the crank arm in the manner described.

30 The advantages of my construction lie in the attachment of the counterbalance weight to the pitman where it may be readily removed from the crank arm of the power when not needed, and when thus removed will 35 be out of the way and assist in the holding of the pitman and walking beam. It serves, therefore, not only as a counterbalance but as a holding means to anchor the pitman and walking beam when the pump is not operated.

40 Having thus described my invention, what I claim as new is:

1. In a pumping rig or the like, a rotatable power shaft, a crank arm thereon, a walking 45 beam, a pitman connected with said walking beam and to said crank arm, a yoke secured to the lower end of said pitman, and a plurality of plates secured detachably to said yoke to form a variable weight upon said 50 pitman.

55 2. In a pumping rig or the like, a rotatable power shaft, a crank arm thereon, a walking beam, a pitman connected with said walking beam and to said crank arm, a yoke secured to the lower end of said pitman, and a plurality of plates secured detachably to said yoke to form a variable weight upon said pit- 60 man, said weight being detachable with said pit-

65 man from said crank arm.

3. In a pumping rig or the like, a rotatable power shaft, a crank arm thereon, a walking beam, a pitman connected with said walking beam and to said crank arm, a yoke secured to said pitman, and a plurality of plates se-

cured detachably to said yoke to form a variable weight upon said pitman.

4. In a pitman, a body member, a bearing element comprising a pair of members movably positioned adjacent one end of the body member, means engageable with the body and one of said members for retaining the bearing element in functioning position, and a weight element attached to the body member.

In testimony whereof I hereunto affix my 75 signature this 25th day of January, A. D. 1928.

FRED GRAHAM.
